UNITED STATES PATENT OFFICE.

FREDERIC GRISCOM, OF DOLINGTON, PENNSYLVANIA.

MAIL-BAG.

SPECIFICATION forming part of Letters Patent No. 297,789, dated April 29, 1884.

Application filed March 31, 1884. (No model.)

To all whom it may concern:

Be it known that I, FREDERIC GRISCOM, a citizen of the United States, residing at Dolington, in the county of Bucks and State of Pennsylvania, have invented certain new and useful Improvements in Mail-Bags; and I do declare the following to be a full, clear, and exact description of the invention, such as will enable others skilled in the art to which it appertains to make and use the same, reference being had to the accompanying drawings, and to the figures and letters of reference marked thereon, which form a part of this specification.

15 My invention relates to fastenings for mail-bags; and it consists in the novel construction, combination, and arrangement of the several parts, as will be hereinafter described and claimed.

20 In the drawings, Figure 1 is a perspective view of a section of the bag opened. Fig. 2 is a section on about line $x x$, Fig. 1, when the bag is closed. Fig. 3 is a section on link $y y$, Fig. 2.

25 The bag A is provided, near its upper end, with staple-openings a , formed through its opposite sides, and arranged so as to register with each other when the bag is closed, as most clearly indicated in Figs. 2 and 3. The 30 lock-staple a' is secured on the front of the bag, in line between the openings a and near one side of the bag, as shown. The covering-flap B is secured at one edge to the back of the bag, and is provided near its opposite edge with a series of openings, b , arranged to coincide with the openings a when the bag is closed. It is also provided with an opening, b' , fitted for the passage of the lock-staple a' . The end 35 of this flap which is secured to the back of the bag is slotted at B' for the passage of the fastening-staples. Strips C C are secured on the back of flap B, above and below slots B' , and have their adjacent edges projected beyond the upper and lower edge of said slots, and 40 providing a guideway for the hooks, presently described. These strips C are notched at intervals, coinciding with slots B' , as most clearly indicated in Fig. 3. Strips D D are secured on the back of strips C, and further apart 45 than said strips, so as to provide a keeper for

the hook-strap. A covering-piece, E, is secured on the strips D D and over the space between the same, as most clearly shown in Fig. 3. These strips C D and piece E are preferably made of leather, and riveted or otherwise suitably secured to the back of the bag, as thereby the construction of the entire device may be formed by the leather-workers. It is manifest, however, that where so desired the casing could be dispensed with, or a metallic box or keeper could be substituted for pieces C D E. The hook-strap F is secured between strips D, and has hooks f operating between the strips C, as clearly shown. One end of this strap is provided with stops f' , and 55 has a slot, f'' , arranged to be slipped over the lock-staple a' . The other end of the strap is secured to the front flap, presently described. I also preferably provide the strap near this end with a tongue, G, whereby it may be withdrawn for the purpose of unfastening the bag. The front flap, H, is secured at its lower edge 60 on the front of the bag, and is provided near its upper edge on its inner face, with staples, h , adapted to be inserted through openings a . 65 It is also provided with an opening, h' , for the lock-staple a' . 70

In operation, when the parts are in the position shown in Fig. 1, and it is desired to close the bag, the covering-flap is turned down 75 between the bag and the front flap. The latter flap is then pressed in against the covering-flap, the staple h passing through into the position shown in Figs. 2 and 3. Now, by drawing the strap from the position shown in Fig. 80 1 to that shown in Fig. 2, the bag is securely fastened by the hooks entering the staple, as shown. To lock the bag, the free end of the strap is brought around and over the lock-staple a' , and a suitable lock is applied to said 85 staple, as will be readily understood.

While I prefer to use the hooks as specified, and to incase the hook-strap as before described, it is obvious that such constructions might be dispensed with, and the bag fastened 90 by simply passing the strap through the ends of the staple which extend in rear of the bag.

It will be seen that by my construction the staples cross the mouth of the bag and serve 95 as efficient means for clamping same closely 100

together. The covering-flap extends over the mouth of the bag, and its free edge is covered by staple or front flap, so that it is in position to insert the hand or an instrument up under 5 the covering-flap and into the bag.

My fastening devices are simple, easily operated, and do not add materially to the weight of the bag.

Having described my invention, what I 10 claim, and desire to secure by Letters Patent, is—

1. The improved mail-bag herein described, consisting of the bag proper provided with staple-openings, the covering-flap, the strap-casing, the front flap, and the fastening-strap provided with hooks, substantially as set forth. 15

2. The combination, with the bag proper having staple-openings *a*, and provided with

staple *a'*, the covering-flap provided with staple-openings *b* and *b'*, the front flap provided with staples *h* and openings *h'*, and the fastening-strap, all arranged and adapted for use substantially as set forth. 20

3. The combination of the bag having staple-openings, the covering-flap, and the front 25 flap of the strap *F*, provided with hooks, and secured at one end to the front flap, and provided near said end with a handle-tongue, substantially as set forth.

In testimony whereof I affix my signature in 30 presence of two witnesses.

FREDERIC GRISCOM.
